Richard Vose

UNITED STATES PATENT OFFICE.

RICHARD VOSE, OF NEW YORK, N. Y.

CAR-SPRING.

SPECIFICATION forming part of Letters Patent No. 351,819, dated November 2, 1886.

Application filed October 15, 1884. Serial No. 145,589. (No model.)

To all whom it may concern:

Be it known that I, RICHARD VOSE, a citizen of the United States, and a resident of the city, county, and State of New York, have invented certain new and useful Improvements 5 in Car-Springs, of which the following, taken in connection with the accompanying drawings, is a specification.

My invention relates to that class of car-springs in which a plurality of spiral coils arranged concentrically with respect to one another are made use of, and especially to that class in which a cylindrical outer and a conical inner spiral coil are employed.

Heretofore, in the construction of springs of this class, it has been the custom to employ a conical coil which was much shorter than the cylindrical coil, and to arrange the former within the latter in such a manner that while 15 it was supported and held at its base in proper relation thereto by being fitted within the same its upper end, which was of smaller diameter, was not so supported, and hence in operation was liable to move laterally across its 20 axes and occasion frequent breakages of said coil.

The object of my invention is to obviate this defect and produce a spring of the class mentioned, in which the interior coil shall be of 25 substantially the same length as the exterior coil, and in which both coils shall be held from lateral movement with respect to each other at both their upper and lower ends.

To this end my invention consists in the 30 combination, with a cylindrical spiral coil, of a conical coil of substantially the same length as the cylindrical coil, arranged within the same, and in various other combinations and arrangements of parts, as hereinafter described, 35 and particularly pointed out in the subjoined claims.

Referring to the accompanying drawings for 40 a better understanding of my invention, A and B are the outer and inner spiral coils, respectively, the former of which is cylindrical and the latter conical in form. These coils are constructed of such dimensions that the exterior of the base of the conical coil snugly 45 fits the interior of the cylindrical coil, and 50 both rest upon the base-plate E, which is provided at a suitable distance from its center

with an upwardly-projecting flange, b, that enters the interior of the base of the inner coil and is clasped thereby. Resting upon the upper end of these coils, which are of substantially the same length, is the top plate or cap, D, having the depending circular flange d cast or otherwise formed on its under side. This flange is of such diameter and thickness in cross-section that its exterior surface snugly 60 fits the interior of the outer coil and its interior surface the exterior of the upper end of the inner coil, so that when the top plate or cap is in position upon the coils it projects down between them and holds them in proper position respecting each other. In the center of both the top plate or cap, D, and the base-plate E is formed a suitable aperture, through 65 which and the inner coil may be passed, if desired, a bolt, by which means and a nut 70 the top plate or cap and the base-plate may be held tightly upon the coils.

By the construction of parts thus described I am able to use not only a conical and a cylindrical coil in connection which shall be of substantially the same length, with the former 75 arranged within the latter, but also to provide means whereby their ends may be held in proper relation with respect to each other, without capability of lateral movement, and 80 produce a spring which shall be simple in construction and reliable in operation.

I have shown the outer coil, A, as constructed of a larger rod than the coil B, and hence capable of withstanding a greater pressure 85 than the latter; but it is to be understood that I do not limit myself thereto, as it is obvious that I may reverse this order and make the interior coil of the larger rod, if I so desire. Neither do I limit myself to the particular arrangement of flanges upon the base-plate and the top plate or cap shown, as this may be modified without departing from the spirit of my invention; or such flanges may be entirely omitted and other equivalent devices employed 90 in lieu thereof and still be within the scope of my invention.

I am aware that it is not new to arrange a spiral volute coil within a cylindrical coil, the said volute coil being formed from a strip or 100 from strips of sheet or plate metal wound into proper shape, as shown, for instance, in Let-

ters Patent No. 255,935, and such I do not claim; but,

Having fully described my invention, what I do claim, and desire to secure by Letters Patent, is—

1. The combination, with a cylindrical spiral coil, of a conical spiral coil of substantially the same length as said cylindrical coil, arranged within the same, whereby a spring is produced in which the conjoint action of a conical and a cylindrical spiral coil is secured during the entire range of movement of said spring, substantially as described.

2. The combination, with the outer cylindrical coil, A, the inner conical coil, B, and the base-plate E, of the top plate or cap, D, provided with a depending flange projecting down between the upper ends of the coils, substantially as described.

3. The combination, with the outer cylindrical coil and the inner conical coil having its base constructed of a size to fit the interior of the cylindrical coil, of a base-plate upon which they both rest, and means for holding the base of said conical coil from lateral movement upon the base-plate, substantially as described.

4. The combination, with the outer cylindrical coil, A, and the inner conical coil, B, having its base constructed of a size to snugly fit the interior of the cylindrical coil, of the base-plate E, provided with the upwardly-projecting flange b, which passes up into the interior of the conical coil and prevents it from moving laterally upon the said base-plate, substantially as described.

5. The combination, with the outer cylindrical coil, A, the inner conical coil, B, having its base constructed of a size to fit the interior of the cylindrical coil, and the base-plate E, provided with the upwardly-projecting flange b, which enters the interior of the conical spring and holds it in place upon said base-plate, of the top plate or cap, D, provided with the depending flange d, which projects down between the upper ends of the outer and inner coils, substantially as described.

RICHARD VOSE.
